UNITED STATES PATENT OFFICE.

ALDEAN W. RAWLING, OF SAN FRANCISCO, CALIFORNIA, ASSIGNOR TO GEORGIE D. BOBO, OF FAIRMEAD, CALIFORNIA.

VICE.

Application filed April 3, 1922. Serial No. 548,928.

To all whom it may concern:

Be it known that I, ALDEAN W. RAWLING, a citizen of the United States, residing at the city and county of San Francisco and 5 State of California, have invented new and useful Improvements in Vises, of which the following is a specification.

This invention relates to vises of the foot-operated type, such as shown for example 10 in the application of William H. Bryan, Jr., Serial No. 508,976, filed October 20th, 1921 (Patent No. 1,417,025, May 23, 1922).

It is frequently desirable to have the head of the vise so mounted that it can be turned 15 angularly on its support so as to permit it to be used in various positions of adjustment, and among the improvements embodied in the present application is a swivel mounting for the head so arranged that the 20 head and connected parts may be turned angularly, while the foot-operated parts remain stationary. Other changes and improvements will become apparent upon a further understanding of the invention.

25 In the accompanying drawing, Fig. 1 shows an end elevation of a vise embodying my invention.

Fig. 2 shows a side elevation of the same.

Fig. 3 shows a plan view of the head of 30 the vise.

Fig. 4 shows a vertical sectional view of the upper portion of the vise illustrating the swivel mounting for the head.

Fig. 5 shows a detail of the connections 35 for operating the toggle links.

Fig. 6 shows an enlarged view, partly in section, of the connections between the toggle links and foot-operated parts.

40 Figs. 7 and 8 show detail sectional views of the locking means for the swivel head.

Referring in detail to the accompanying drawings, a bench is shown at 9 and at the front thereof is a vertical post 10. Carried upon the post and bench is a circular flange 45 plate 11 forming a support for a turn-table 12. The turn-table has a stationary jaw 13 and a movable jaw 14, the latter having a shank 15 slidably fitted in a sleeve or guide 16 formed integral with the turn-table and stationary jaw. The bottom of the shank 50 15 is provided with ratchet teeth 17 for co-operation with a pawl 18, which pawl is pivotally mounted on a transverse pin 19 working in slots 20 formed in the turn-table 12. The heel of the plate is weighted so as

to insure engagement of the nose of the pawl with the ratchet teeth 17.

Connected also to the pin 19 is a toggle link 21, the other end of which is pivotally connected with a similar toggle link 22, the latter being pivotally connected to the turn-table. These two toggle links are connected at their adjacent ends with a thrust rod 23, which rod has a ball and socket joint 24 connecting it with a short arm 25 on a bell 60 crank lever 26. The bell crank lever is pivotally mounted, at 28, upon a bracket 29 fixed to the upper end of the post 10, and at the lower end of the bell crank lever is a forwardly extending arm 30 forming a pedal 65 for operating the bell crank lever. This extension 30 projects through an opening in the lower end of the post 10. The under side of the extension is provided with teeth 31 and co-operating with said teeth is a 70 pinion 32 carried on a swinging arm 33, which arm is held normally in raised position by a spring 34, so that the pinion engages the teeth 31. This pinion is held against turning movement in one direction 75 by means of pawls or dogs 35. The swinging arm has a bifurcated extension 36 at its forward end and forming a tread portion so that the operator may readily depress the arm by placing his foot thereon, 80 whereby to disengage the pinion 32 from the teeth 31.

The bell crank lever is normally held with its extension 30 projecting forwardly by means of a coiled spring 37 connected to 90 the lower end of the bell crank and to the post 10. In this position the short arm 25 of the bell crank lever is inclined downwardly and the toggle links 21 and 22 are flexed so that the pawl 18 is retracted. In re-95 tracted position, the heel of the pawl engages a cam 38 on the turn-table and raises the heel of the pawl, thereby disengaging the nose or tooth of the pawl from the ratchet teeth 17. At this time the movable jaw of 100 the vise is unlocked. When it is desired to bring the jaws together the operator pulls forwardly and downwardly on the extension 30 of the bell crank lever, thereby stroking the toggle links and causing the pawl 18 to 105 ride clear of the cam to engage the ratchet teeth 17 for the purpose of thrusting the sliding shank inwardly the required distance to clamp the jaws tightly against the work.

The turn-table 12 is held on its support- 110

ing ring 11 by means of a locking ring 39 detachably fitted to the bottom of the turn-table and projecting beneath an internal flange 40 on the supporting ring. This prevents the turn-table from being accidentally removed from its supporting ring. For the purpose of locking the turn-table against turning movement, I provide a friction block 41, as best shown in Figs. 7 and 8. This block lies within a pocket 42 in the annulus of the supporting ring 11 and is adapted to co-operate with the adjacent wall of the turn-table. A screw 43 having an operating handle 44 is provided for clamping the friction block tightly against the turn-table whereby to prevent the latter from turning. The ball and socket connection 24 between the stationary and movable parts of the device permits the turn-table to be moved angularly 360° without interfering in any way with the operating connections.

Various changes in the construction and arrangement of the several parts herein shown and described may be employed without departing from the spirit of my invention as disclosed in the appended claims.

Having thus described my invention, what I claim and desire to secure by Letters Patent is:

20 1. A bench vise of the foot-operated type comprising a supporting frame having a stationary ring, a turn-table mounted on the ring, a stationary jaw on the turn-table, a shank slidably mounted on the turn-table 35 and carrying a jaw to co-operate with the stationary jaw, said shank being provided with teeth, a movable pawl carried upon the turn-table to engage the teeth on the shank, toggle links connected to the turn-table and 40 to the pawl for actuating the latter, a foot-operated device carried on a stationary part of the frame for actuating said toggle links and a swivel connection between the foot-operated mechanism and the links permitting the turn-table and associated parts to 45 be rotated.

2. A bench vise of the foot-operated type comprising a supporting frame having a stationary ring, a turn-table mounted on the ring, a stationary jaw on the turn-table, a shank slidably mounted on the turn-table and carrying a jaw to co-operate with the stationary jaw, said shank being provided with teeth, a movable pawl carried upon the turn-table to engage the teeth on the shank, toggle links connected to the turn-table and to the pawl for actuating the latter, a foot-operated device carried on a stationary part of the frame for actuating said 55 toggle links, a swivel connection between the foot-operated mechanism and the links permitting the turn-table and associated parts to be rotated, and means for locking the turn-table and stationary ring in any 60 position of adjustment.

3. A bench vise of the foot-operated type comprising a supporting frame including a stationary ring, a turn-table rotatably mounted on the ring, a stationary jaw on the turn-table, a shank slidably mounted on the turn-table and carrying a jaw to co-operate with the stationary jaw, said shank being provided with teeth, a movable pawl carried upon the turn-table to engage the teeth on the shank, toggle links arranged within the turn-table, one of said links being connected to the turn-table and the other connected to the pawl for actuating the latter, a thrust link pivotally connected to said toggle links for operating the latter, a foot-operated bell crank mounted upon the stationary part of the frame for operating said thrust link and a ball and socket connection between the foot-operated bell crank and thrust link whereby to permit the turn-table 85 and connected parts to be rotated without interfering with the operating connections for the vise.

4. A bench vise of the foot-operated type comprising a frame having a stationary ring 90 formed with an internal flange, a turn-table rotatably mounted on the ring, a locking ring fastened to the turn-table and extending beneath said flange on the stationary ring, a stationary jaw on the turn-table, a shank slidably mounted on the turn-table and carrying a jaw to co-operate with the stationary jaw, said shank being provided with teeth, a pawl slidably mounted within the turn-table for engagement with the teeth 100 on the shank, toggle mechanism carried within the turn-table for actuating the pawl and foot-operated mechanism mounted upon a stationary part of the frame for actuating said toggle mechanism and a connection between the foot-operated mechanism and toggle links permitting the latter to be turned with the turn-table.

5. A vise comprising a frame having a stationary ring, a turn-table rotatably mounted 110 on the ring, a stationary jaw on the turn-table, a shank slidably mounted on the turn-table and carrying a jaw to co-operate with the stationary jaw, said shank being provided with teeth, a sliding pawl carried by 115 the turn-table for engagement with the teeth on the shank, toggle links carried upon the turn-table for actuating the pawl, operating mechanism for the toggle links mounted upon a stationary part of the frame, connections between said operating mechanism and the toggle links permitting the latter to be turned with the turn-table and means to lock the turn-table against turning movement, said means comprising a friction device interposed between the stationary ring and turn-table and means for clamping the same tightly between the parts.

ALDEAN W. RAWLING.
